UNITED STATES PATENT OFFICE.

FRANK W. SHUPERT, JOSEPH WORMALD, AND HENRY L. SHUPERT, OF HILLYARD, WASHINGTON.

FIRE-BRICK.

SPECIFICATION forming part of Letters Patent No. 761,418, dated May 31, 1904.

Application filed August 28, 1903. Serial No. 171,149. (No model.)

To all whom it may concern:

Be it known that we, FRANK W. SHUPERT, JOSEPH WORMALD, and HENRY L. SHUPERT, citizens of the United States, residing at Hilliard, in the county of Spokane and State of Washington, have invented a new and useful Fire-Brick, of which the following is a specification.

This invention relates to fire-brick, and more particularly to fire-brick used as arches in the fire-boxes of locomotive-engines and other fire-boxes in which heat of similar intensity is developed.

In the arches of fire-boxes of locomotive-engines, especially modern high-power engines in which steam is maintained at a pressure of from two hundred to two hundred and twenty-five pounds to the square inch, the fire-brick are subject to heat of great intensity, which tends to disintegrate the brick with great rapidity, and, moreover, the high speed of the engine causes much swaying and jarring of the engine, together with a certain amount of distortion of the contour of the fire-box, which tends to break the brick before they are disintegrated by the action of the heat developed in the fire-box. The feeding of coal into the fire-box in engines of the type above specified is another source of injury to the fire-brick, as, owing to the forced draft employed, the coal is drawn into the fire-box with unusual velocity.

Owing to all of the conditions noted in the preceding paragraph, the fire-bricks which form the arches of the fire-boxes of locomotive-engines deteriorate very rapidly, the life of the fire-brick being in some instances as short as a week.

The object of this invention is to provide a fire-brick especially designed for use in the construction of the arches of the fire-boxes of modern locomotive-engines and capable of resisting the jars, strains, and excessive heat to which fire-bricks so used are subjected without breaking or disintegrating for a period very much longer than that which usually suffices to render the ordinary fire-bricks unfit for further service.

In attaining the object above stated we make use of the fire-brick illustrated in two slightly-

different forms in the accompanying drawings, described in the following specification, and having the novel features thereof pointed out in the appended claims.

In the drawings, Figure 1 is a view in longitudinal section through a fire-brick, illustrating one form of embodiment of the invention. Fig. 2 is a view in longitudinal section through a fire-brick, showing a modified form of the invention.

In the drawings corresponding parts are designated by the same characters of reference in both views.

Referring to the drawings by reference characters, 1 designates the main portion of the brick, formed, as usual, of fire-clay.

2 are metal rods, preferably iron, extending through the brick from end to end thereof, as shown.

3 designate channels in the brick, within which are inclosed the metal rods which strengthen the brick for use as specified.

In the form of the invention shown in Fig. 1 the brick is made with channels 3, extending through it, each channel having at either end a countersunk portion 5. The rods 2 are inserted into the channels after the bricks are baked, and each rod is held in place by means of a nut and washer at one end and a bolt-head and washer at the other end, as shown. The countersunk openings in the ends of the brick are filled up with asbestos and clay after the rods are inserted, which forms a protecting-covering over the ends thereof.

In the form of the invention shown in Fig. 2 the metal rods provided with asbestos coverings 4 are laid in the fire-clay of which the brick is made before the brick is subjected to pressure in the mold to compact it before baking. The ends of the rods are left uncovered during the baking of the brick in order to permit the clay of which the brick is formed to shrink, as it always does during the baking process, without causing injury to the ends of the brick from the rods incased within the brick. After the brick is baked the openings in the ends are filled in with fire-clay, as in the form of the invention already described.

As is well known to the makers of brick

fire-clay contracts about one inch in twelve during the baking process, and the temperature at which the baking is carried on causes an appreciable degree of expansion in the metal. For this reason it is necessary to provide between the metal rods and the fire-clay of which the brick is formed a yielding sheet or covering for the rods which will permit the shrinkage of the fire-clay forming the brick without splitting the brick. Before the brick are baked they are subjected to very heavy pressure to thoroughly compact the clay of which they are made, and the fibers of the asbestos which are used in making the coverings of the metal rods are considerably compressed thereby; but sufficient compressibility is still left in the asbestos after the molding of the brick by pressure to permit the shrinkage which inevitably occurs during the baking process.

Bricks constructed as described in the foregoing paragraphs are adapted to withstand the shocks, strains, and intense heat to which the fire-brick arches of the fire-boxes in locomotives are subjected for a much longer time than the ordinary form of fire-brick, and they are also adapted to stand handling and shipment much better than the ordinary form of fire-brick, as will be readily seen.

In both of the forms of embodiment of the invention described and illustrated the metal rods are shown as extending longitudinally through the brick, as the bricks are most apt to be broken by strains which are best resisted by longitudinally-disposed rods; but it is obvious that the rods may be placed in other positions in the brick and accomplish the same results contemplated in our invention. Hence we do not desire to limit ourselves to any special mode of disposition of the rods within the brick. The rods shown in the drawings are round rods; but it is obvious that rods of other configurations may be used instead without sacrificing any of the advantages obtained by our system of strengthening, and any well-

known form of rod may be substituted for the round rods shown.

While the asbestos covering has been shown only upon the rods placed in the brick prior to the baking process, as that form of brick 50 is the only one in which asbestos covers are a necessity, it will be understood that asbestos covers may be employed, if desired, upon the rods in the embodiment of the invention shown in Fig. 1. 55

Having thus described the construction and use of our invention, what we claim as new, and desire to secure by Letters Patent, is—

1. A fire-brick consisting of a body portion of fire-clay and containing an internal 60 strengthening structure composed of metal rods incased in non-combustible, compressible coverings.

2. A fire-brick comprising a body portion of baked fire-clay and a plurality of iron rods 65 with asbestos covers disposed through said body portion.

3. The combination with a fire-brick having channels therethrough, of a plurality of metallic bolts disposed one in each channel, nuts 70 and washers to hold said bolts securely in place, and plugs of asbestos and fire-clay over the ends of said bolts.

4. The combination with a fire-brick having a plurality of channels extending therethrough, each channel having at each end a counterbored portion, of a plurality of metallic bolts disposed one in each channel, nuts and washers to hold said bolts in association with the brick, and plugs of fire-clay and asbestos over the ends of said bolts. 75 80

In testimony that we claim the foregoing as our own we have hereto affixed our signatures in the presence of two witnesses.

FRANK W. SHUPERT.
JOSEPH WORMALD.
